Application February 9, 1950, Serial No. 7,844

Term of patent 7 years

(Cl. D58—26)

To all whom it may concern:

Be it known that I, Ladislas Medgyes, a citizen of United States of America, residing at 2 East 56th Street, in the county of New York and State of New York, have invented a new, original, and ornamental Design for a Bottle Cap, of which the following is a specification, reference being had to the accompanying drawing, forming part thereof.

In the drawing—

Figs. 1 and 3 are top and bottom plan views, respectively, and Fig. 2 is a front view of a bottle cap, showing my new design. The stippling shown in the drawing is intended to represent a texture like that of crystallized snow.

I claim:

The ornamental design for a bottle cap, as shown and described.

LADISLAS MEDGYES.
